EX

DESIGN FOR A GATE.

Design No. 12,928, dated May 16, 1882.

UNITED STATES PATENT OFFICE.

HENRY FALLER, OF MIDDLE VILLAGE, ASSIGNOR TO JOHN TIMMES, OF BROOKLYN, NEW YORK.

DESIGN FOR A GATE.

SPECIFICATION forming part of Design No. 12,928, dated May 16, 1882.

Application filed March 30, 1882. Term of patent 7 years.

To all whom it may concern:

Be it known that I, HENRY FALLER, a citizen of the United States, residing at Middle Village, in the county of Queens and State of New York, have invented a new and original Design for Gates, of which the following is a specification.

The accompanying photographic illustration represents a front view of the gate.

- 10 The letter A designates the top piece, and B the base piece, of the gate, connected together at the ends by the posts C. The top piece, A, is arched, and is surmounted by three spires, d, one in the center and one at each end thereof, and by scrolls e between or intermediate of the spires, the whole being ornamented in the Corinthian order of architecture. Intermediate of the posts C are two vertical bars, f, extending from the top to the bottom piece 15 and forming three spaces, containing the following elements: In the central space, and resting on the base piece B, are two arches or foiles, g, intersected by vertical stems h, which are bifurcated at their opposite ends and meet the top and base pieces, respectively. In said central space, moreover, is a quadruple scroll, i, whose members are arranged to embrace the bifurcated stems h between their ends. In the 20 respective side spaces formed by the vertical bars F is an arch, k, which, like the arches g,

rests on the base piece, B, and which is intersected by the lower part of a sectional stem, l, having each part thereof bifurcated at its opposite ends. The upper and lower parts of this sectional stem l meet the top and base pieces, respectively, and upon the central part thereof are two double scrolls, o, one impinging against the other.

What I claim as new, and desire to secure by Letters Patent, is—

1. The design for a gate, consisting of the arched top piece, A, the spires d, and the scrolls e, as shown and described.

2. The design for a gate, consisting of the vertical bars f, the arches g, the bifurcated stems h, and the quadruple scroll i, as shown and described.

3. The design for a gate, consisting of the vertical bars f, the arches k, the sectional stems l, and double scrolls o, as shown and described.

4. The design for a gate, consisting of the vertical bars f, the arches g k, the stems h l, and scrolls i o, as shown and described.

In testimony whereof I have hereunto set my hand and seal in the presence of two subscribers.

HENRY FALLER. [L. S.]
